UNITED STATES PATENT OFFICE

109,071

DESIGN FOR A GAS RANGE

Elmer D. Pellegrin, Woodstock, Ill., and Thomas H. Hall, Los Angeles, Calif., assignors to Geo. D. Roper Corporation, Rockford, Ill., a corporation of Illinois

Application December 24, 1937, Serial No. 73,856

Term of patent 14 years

To all whom it may concern:

Be it known that we, Elmer D. Pellegrin and Thomas H. Hall, both citizens of the United States, residents of Woodstock, McHenry County, Illinois, and Los Angeles, Los Angeles County, California, respectively, have invented a new, original, and ornamental design for a Gas Range, of which the following is a specification, reference being had to the accompanying drawing, forming part thereof.

In the drawing:

The figure is a perspective view of a gas range,

showing our new design, the end which does not show in this view is like the other end illustrated.

The small circles appearing on the front panels indicate the locations for handle attachments and gas cock and oven regulator knobs which are omitted.

We claim:

The ornamental design for a gas range, substantially as shown and described.

ELMER D. PELLEGRIN.
THOMAS H. HALL.
